DOOR CONSTRUCTION

David C. Crawford, Detroit, Mich., assignor to
 Crawford Door Company, Detroit, Mich., a corporation of Michigan

Application December 18, 1944, Serial No. 568,641

6 Claims. (CL 20—35)

This invention relates to door constructions especially adapted for upward acting doors of the tilting type.

Specifically, the invention relates to a doorway closure construction wherein a pair of identical door sections are held together to form a one-piece closure by means of door hardware having tangs, lugs, or other projections seated in longitudinal grooves formed in the stiles of the door sections and abutting the rails of the door sections to carry the load of the closure.

In accordance with this invention, the end stiles of a door are formed with longitudinally extending grooves in their outer edges. The rails of the door extend into flush relation with the outer edges of the stiles and thus automatically form ends or abutments for the grooves. One rail of each door is formed with a double male and female joint surface to mate with an identically formed surface on the rail of another door. Mated doors are held together by means of door hardware which includes lugs or tangs extending into the grooves of the stiles in abutting relation with the rails which form the ends of the grooves. This door hardware is preferably in the form of two channel strips each having side legs overlying the inner and outer faces of the doors and a connecting web with inturned tangs projecting into the grooves of the stiles, and abutting the rails. This connecting web also has holes for receiving fasteners such as screws, nails or the like which are driven into the stiles thereby connecting the channel strips to the edges of the door, and forming a one-piece closure member from a pair of doors.

The doors preferably have panels seated in grooves formed in the inner edges of the rails and stiles. Since the tang-receiving grooves of the stiles are in the outer edges of the stiles, both the panel-receiving grooves and the tang-receiving grooves can be simultaneously cut in the stiles.

An object of this invention is to provide a closure for upward acting door constructions wherein a minimum number of parts are used.

A further object of the invention is to provide a closure composed of secured-together identical doors having mating double male and female surfaces on adjoining rails thereof.

A still further object of the invention is to provide a closure composed of a pair of identical doors having longitudinally grooved outer stiles with rails forming abutments in the grooves and receiving load-carrying projections of door hard-

ware which holds the doors in mated relationship.

A still further object of the invention is to provide a closure for tilting type upward acting doors which has longitudinally grooved stiles for receiving upward acting door hardware.

Other and further objects of the invention will be apparent to those skilled in this art from the following detailed description of the annexed sheet of drawings which, by way of preferred example, illustrates one embodiment of the invention.

On the drawing:

Figure 1 is an elevational view of a closure or door according to this invention.

Figure 2 is a longitudinal view of one of the channel strips of the door of Figure 1.

Figure 3 is a fragmentary enlarged vertical cross-sectional view taken along the line III—III of Figure 1.

Figure 4 is an enlarged elevational view, with parts broken away and shown in vertical cross section, of a portion of the closure construction of Figure 1.

Figure 5 is a horizontal cross-sectional view taken along the line V—V of Figure 4.

As shown on the drawing:

As shown in Figure 1, the closure 10 is composed of two identical doors 11, 11, held in superimposed relation by metal channel strips 12, 12. The doors 11 have rails 13, 13 in mated abutting relation. A rail 14 for the upper door 11 forms the top rail for the closure 10. A rail 14 for the bottom door 11 forms the bottom rail for the closure. End stiles 15, 15 are disposed between and connect the rails 13 and 14 of each door.

The illustrated doors 11 each have four panels 16, but it should be understood that single panel doors, or doors with any number of panels, can be used without departing from the scope of this invention. The panels 16 of each door are separated by two middle rails 17 and a munition 18. The middle rails 17 extend between the stiles 15 and the munition 18. The rails, stiles, middle rails and munition are grooved to receive the peripheral edges of the panels 16 as is customary in panel door construction.

As best shown in Figures 4 and 5, the rails 15 of each door 11 have longitudinal grooves 19 in the outer edges thereof. These grooves 19 extend throughout the entire length of the stiles, and are readily formed therein simultaneously with the forming of the grooves for receiving the panels 16. Thus a stile can be run through a grooving machine to be grooved along both edges

thereof and, since one groove is necessary for the panels 16, the other groove 19 can be formed at no extra cost.

The rails 13 and 14 of each door 11 extend flush with the outer edges of the stiles 15 and thus provide abutments or end walls for the grooves 19. As illustrated in Figure 4, the rails 13, 13 provide end walls or abutments 13a for the grooves 19 and, as illustrated in Figure 1, the rails 14 provide end walls or abutments 14a for the other ends of the grooves.

As best shown in Figure 3, the rails 13 of each door 11, 11 having mating ends provided with a double male and female groove to provide an interfitting lock for holding the doors in aligned relationship along their entire widths. Thus each rail 13 has a flat end portion 13b, a groove 13c extending inwardly from the flat end 13b and having a rounded bottom merging into a sloping wall which extends beyond the flat portion 13b to form a tongue 13d. This tongue has a rounded end with a straight side wall opposite the sloping side wall thereof, and this straight side wall terminates at a flat end portion 13e level with the end portion 13b. Since these end surfaces of the rails 13, 13 are identical, the doors are placed in superimposed relationship and the tongue 13d of one door rail 13 will fit in the groove 13c of the other door rail 13 thus forming a double male and female joint arrangement providing an interlock along the entire width of the door.

Each metal strip 12 has flanges or legs 12a, 12a for overlying the inner and outer faces of the stiles 15, and a connecting web or base portion 12b for overlying the outer edges of these stiles 15. As shown in Figure 1, the channel strips 12, 12 extend from the top to the bottom of the closure.

The connecting web 12b of each channel strip has a plurality of inturned tangs 20 cut from metal of the web and bent inwardly to provide vertical lugs. These tangs 20 are so positioned on the web 12b as to extend into the rail grooves 19 as best shown in Figures 4 and 5. In addition, as best shown in Figures 1 and 4, the tangs 20 are so positioned along the length of the strips 12 as to thrust against the abutting surfaces 13a and 14a of the rails 13 and 14 at the end of the grooves 19.

The thrusting contact between the tangs and the rails in the stile grooves 19 not only serves to properly align the channel strips on the closure 10, but also serves to transfer the load or weight of the door to the channel strips and these channel strips, in turn, mount the door in a doorway on hardware (not shown).

The channel strips 12 have holes 21 at spaced intervals along the lengths thereof as shown in Figure 2, and these holes receive screws or other fasteners 22 as best shown in Figure 4. The screws are driven into the rails 15 to connect the channel strips to the door. Obviously nails, or other types of fasteners, could be used because these fasteners do not carry the weight of the door, and only function to attach the strips to the door.

From the above descriptions it should be understood that upward acting closures are provided by securing, in abutting superimposed relation, a pair of identical doors through the use of end strips which have tangs or other projections extending into grooves in the door stiles for abutting against the door rails to carry the weight of the door. The superimposed doors are maintained in aligned relationship across their entire widths by means of a double male and female joint surface on the abutting rail of each door.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A closure comprising a pair of doors in superimposed relation having abutting rails with interfitted tongues and grooves, said doors having longitudinal grooves in the stiles thereof, and the rails of the doors extending across said grooves in the stiles to form abutment surfaces, channel strips having legs overlying the inner and outer faces of the superimposed doors together with webs overlying the edges of said doors, said webs having inturned tangs extending into the grooves of the stiles in thrusting engagement with the abutment surfaces of said rails, and fasteners connecting the channel strips to the doors.

2. A closure comprising a pair of identical wooden doors in superimposed relationship, each of said doors having stiles with longitudinal grooves extending along the entire lengths thereof in the outer edge surfaces thereof, each of said doors having rails at the tops and bottoms thereof connected to said stiles and extending flush with the outer ends of the stiles to form abutment surfaces for the grooves, strips securing said doors in superimposed relationship with adjoining rails in tight abutting relation, said strips having projections thereon extending into said grooves in abutting relation with the abutment surfaces of the rails for transferring the weight of the closures to the strips and for holding the doors in tight abutted together relation, and fasteners connecting the strips to the doors.

3. A closure comprising a first door having a bottom rail, a top rail, and a pair of stiles interposed between the rails, each of said stiles having a longitudinal groove on the outer edge thereof, said top rail having a top surface with an adjacent tongue and groove extending along the length of the rail, a second door having a bottom rail with an adjacent tongue and groove in mated interfitting relation with the tongue and groove of the top rail of the first door, a top rail on said second door, stiles on said second door interposed between said bottom and top rails of the second door, said stiles on said second door having longitudinal grooves in the outer edges thereof terminating at said bottom and top rails, metal channel strips having legs extending from the top to the bottom of the closure and embracing the inner and outer faces of the stiles of both doors together with a connecting web covering the outer edges of the rails and stiles of both doors, said web having inturned tangs extending into the grooves of the stiles and positioned to abut the rails, and fasteners extending through said webs of the channel strips for uniting the channel strips to the doors.

4. A door construction comprising a plurality of door members having interfitted abutting rails and longitudinally grooved stiles, said rails extending across the ends of the grooves to provide abutment surfaces, connecting strips extending from the top to the bottom of the closure having projections seated in said grooves in abutting relation with the abutment surfaces of the rails, and fasteners securing the strips to the closure.

5. A closure member comprising a door having longitudinally grooved end stiles and top and bot-

tom rails extending across the grooves of said end stiles to provide abutment surfaces, and door supporting hardware having projections seated in said grooves in thrusting relation with said abutment surfaces of the rails to carry the weight of the door.

6. A closure comprising a pair of aligned doors

having adjoining edges in edge to edge relation, said doors having grooved outer edges at the ends of said adjoining edges in angular relation thereto, abutments in said grooves, and a strip secured on said doors having projections seated in said grooves in thrusting relation with said abutments.

DAVID C. CRAWFORD.
